United States Patent Office.

IMPROVEMENT IN LANTERNS.

RICHARD CHESTER, OF CHICAGO, ILLINOIS.

Letters Patent No. 60,139, dated December 4, 1866.

SPECIFICATION.

TO ALL WHOM IT MAY CONCERN:

Be it known that I, RICHARD CHESTER, of Chicago, in the county of Cook, and State of Illinois, have invented a new and useful Improvement in Lanterns; and I do hereby declare that the following is a full, clear, and exact description of the same, reference being had to the accompanying drawings, and the letters and figures marked thereon, which form part of this specification.

My said invention consists in arranging, between the case of the lantern and the lamp, a perforated jacket, and connecting therewith an annular support for the glass globe, having a flange projecting outward to the case of the lantern above the perforated jacket, so as to cause the wind which enters the ordinary holes at the sides to pass through said perforated jacket before coming in contact with the flame, thus breaking and diffusing the currents of air and preventing the extinguishing of the flame. To enable those skilled in the art to understand how to make and use my invention, I will proceed to describe the same with particularity, making reference in so doing to the aforesaid drawings, in which—

Figure 1 represents a side elevation of my invention.

Figure 2 a vertical central section of the same; and

Figure 3 a top view of the support for the glass globe and its flange aforesaid.

Similar letters of reference in the different figures denote the same parts of my invention.

A represents the base of the lantern, into which the lamp L is placed through the bottom, and secured by means of the spring catches, S, which extend over the projection b, as shown. Between the lantern case and the lamp is arranged the annular enclosure marked c d, which rests upon the aforesaid projection b, and is firmly braced in the proper position by means of the exterior flange, e, extending out to the casing, as shown. The part marked c is perforated, as shown, while the part marked d is not, and the flange or diaphragm, e, causes the air which enters through the holes a, in the case, to pass through the perforated jacket, c; to supply the flame with air, while the force of the wind is broken thereby, and the extinguishment of the flame or light, which would otherwise occur, is effectually prevented. c', represents a second perforated jacket similar to the one marked c, attached to the diaphragm exterior to the said jacket, c, which serves more effectually to break the force of the wind while admitting the air to support the flame as desired. The entire device, c c', d, e, may be made removable or permanently attached to the lantern, as preferred. The lower end of the globe enters the support, d, while the upper end is supported in the top, C, as shown. The guards, E, are fastened to the lantern top, and to a band, F, which is hinged upon one side to the case, A, and is secured to the opposite side by a catch, G, so as to be opened when desired to remove the globe, whose support, however, is not upon the guard band, F, but is entirely independent thereof. D represents passages for allowing the heated air to pass out at the top of the lantern, while at the same time the wind is directed through the top without being deflected downward upon the flame.

Having described the construction and operation of my invention, I will proceed to specify what I claim and desire to secure by Letters Patent:

I claim the combination and arrangement, with a lantern and its globe, of the globe support d, perforated jackets c c', and diaphragm e, arranged and operating as and for the purposes specified.

RICHARD CHESTER.
